UNITED STATES PATENT OFFICE.

FRANK MOSSBERG, OF ATTLEBORO, MASSACHUSETTS, ASSIGNOR TO MOSSBERG PRESSED STEEL CORPORATION, OF ATTLEBORO, MASSACHUSETTS, A CORPORATION OF MASSACHUSETTS.

TUFT-YARN SPOOL.

Application filed August 19, 1922. Serial No. 532,883.

To all whom it may concern:

Be it known that I, FRANK MOSSBERG, a citizen of the United States, residing at Attleboro, in the county of Bristol, Commonwealth of Massachusetts, have invented 5 certain new and useful Improvements in Tuft-Yarn Spools, of which the following is a specification.

This invention relates to tuft-yarn spools 10 for use on looms for weaving moquette or other tufted fabrics, and consists particularly of improvements in the form and structure of the spool.

One object of the improvement is to provide a spool for the purpose specified which will be light in weight yet strong and staunch in structure and capable of resisting rough handling in use.

Another object of the improvement is to 20 provide a spool having a minimum number of parts which may be constructed of sheet-metal to economize in the cost of manufacture of the spool.

Another object of the improvement is to 25 provide an economical method of assembling or joining the parts of the spool together without the use of pins, bolts, screws or other machined elements.

Another object of the improvement is to 30 provide means on the barrel of the spool for holding the ends of the yarns to be wound thereon, which said means may be constructed integral with the barrel itself.

Further objects of the improvement are 35 set forth in the following specification which describes several preferred embodiments of the invention as illustrated in the accompanying drawings. In the drawings:

Fig. 1 is a view showing a plurality of 40 my improved spools arranged in series and coupled together to rotate in unison, a portion of the spools being illustrated in longitudinal section on the vertical plane of their axis;

Fig. 2, a similar sectional view showing 45 a modification in the structure of the barrel of the spool and its end-coupling or clutching means;

Fig. 3, a perspective view of one of the 50 end-heads or flanges of the spool;

Fig. 4, a cross-sectional view of the barrel 55 of the spool;

Fig. 5, a view in perspective of the coop-

erating coupling-elements of the spools which form the end-journals thereof; 55

Fig. 6, a similar view showing a modified form of coupling-elements; and

Fig. 7, a similar view showing still another form of coupling-elements.

My improved spool is intended for use on 60 the frames of tuft-yarn carriers of broad looms in which a plurality of the spools holding the tuft-yarns are arranged in series with their axes in alinement, and coupled together to rotate as a unit when the yarns 65 are unwound therefrom. The spools are adapted to be uncoupled and removed individually from the frames of the carriers of the loom so that they may be more easily handled as single units in winding the yarn 70 thereon and transporting the spools about the mill.

In Fig. 1 I have illustrated three aligned and connected spool units 2, 3 and 4, or what might be termed a continuous spool 75 composed of three connected sections. Each spool unit comprises a cylindrical barrel 5 having end-heads or flanges 6 and 7. The end-heads 6 of the center spool 3 consist simply of disk-like flanges, while the two outer heads 7 of the end spools 2 and 4 are constructed with overhanging annular rims 8 which serve as brake-drums adapted to be engaged by friction-bands (not shown) or to be operated upon by other means for 85 checking the rotation of the spool in the usual manner as well known in the art.

In order to render the spool of minimum weight, yet strong and staunch in structure, I preferably form its barrel 5 from a hollow 90 cylinder or sheet-metal tube. The barrel 5 may be constructed from a flat strip or blank rolled into a tube with its longitudinal edges abutting in a closed seam at 10. As shown in Fig. 4, the abutting portions of the tube 95 are crimped or folded over to project their edges outwardly at the seam 10, and are preferably brazed or welded together to insure a stronger structure capable of resisting torsional strains. In this manner I provide a narrow, upstanding rib 11 extending longitudinally of the exterior of the barrel 5, with its surface preferably roughened or knurled as shown in Fig. 1 to adapt the rib 100 to hold the ends of the yarns wound onto the spool.

At the extremities of the barrel 5 I form projecting tabs or lugs 12 which are inserted through slits 14 in the end-heads 6 and 7, see Fig. 3, and headed over as shown in Fig. 1 to fasten the heads securely in place against the ends of the barrel. The heads 7 carrying the brake-rims 8 are provided with hubs 15 which are formed with reduced portions 16 riveted through holes 17 arranged axially thereof. Projecting outwardly from the hubs 15 are reduced gudgeons 18 which serve as the outer journals for the connected spools and are adapted to turn in the bearings 19 on the end-standards 20 of the carrier-frame (not shown). Between the two end-standards 20 on the frame are a number of similar standards 21 provided with capped boxes or bearings 22 for supporting the inner gudgeons or journals of the end spools 2 and 4 and the coaxial journals of the intermediate spool 3. While I have shown only one of the intermediate spools 3 in Fig. 1 it is to be understood that a greater number of these may be used when required. The standards 21 have larger bearings than those of the end-standards 20 and their caps 23 are held thereon by the usual means (not shown) to adapt them to be removed to permit the spools to be readily placed in and withdrawn from the bearings.

My improved type of gudgeon-coupling or journal 25 for these intermediate bearings is constructed from sheet-metal rolled into a ring, or it may consist of a short section 35 cut from tubing. Fig. 5 illustrates one form of the gudgeons 26 and 27 for two abutting spools, each of which is constructed as a ring with projecting lugs 28 adapted to be inserted through slits 29 in the spool head 6, see Fig. 3, and headed over as shown in Fig. 1. In this manner the gudgeons 26 and 27 are securely fastened to the heads 6 without the use of pins, screws, nuts, or other machined parts.

The two abutting gudgeons 26 and 27 have their cooperating ends formed to provide an interengaging male-and-female clutch or coupling, as shown in Fig. 5. One of the gudgeons 26 is cut away at its end to provide four equidistant slots 30 adapted to receive a pair of projecting lugs or prongs 31 on the gudgeon 27. The gudgeon 27 might be constructed of identical form with that of the gudgeon 26, but preferably I employ 55 only two engaging-lugs on one of the gudgeons so that the connected spools may be individually applied to or lifted out of the bearings and their cooperating clutching-elements engaged or disengaged without displacing the spools endwise of their bearings.

Fig. 6 illustrates another form of gudgeons or clutching-elements 33 and 34 adapted to be employed in place of those first described. In this embodiment of the invention the 65 tubular gudgeon is slotted at 35 around one-

half of its circumference and the strip of metal thus cut away is bent across the end of the tube to form a diametrical rib or key 36. The free end of the rib 36 may be brazed at the joint 37 when it meets the edge of the longitudinal cut in the tube, and both gudgeons 33 and 34 are of the same form, the drawing illustrating the parts in reverse positions in Fig. 6. When the two gudgeons are arranged in this manner at the abutting ends of adjacent alining spools their ribs 36 will engage one against the other to effect the coupling between the spools.

In Fig. 7 the gudgeons 38 and 39 are shown as constructed in the form of cups struck up from flat blanks. One of the gudgeons 38 has a diametrically-extending slot 40 cut through its flat end-face, while the other cooperating element 39 is formed with a corresponding diametrical rib or key 41 adapted to engage the slot. Fig. 2 illustrates the manner in which the two gudgeons 38 and 39 interengage with a spline and key connection to couple the adjacent alined spools to rotate together.

Fig. 2 also illustrates a modified form of construction for the barrel of the spool. In this embodiment of the invention the barrel 45 may consist of a wooden cylinder having its ends inserted into cylindrical flanges or sockets 46 fastened to the heads 6 by means of the riveted lugs 47.

In use my improved spool units are arranged in axial alinement with their gudgeons journaled in the bearings of the standards 20 and 21 which are mounted on the carrier-frame of the loom. By removing the caps from the bearings on the standards the spools may be applied individually to position therein, and as their journals seat in the bearings the ends of the gudgeons will interengage to clutch or couple the several units together so that they will rotate as one under the control of the braking means acting against the outer heads of the end spools.

It will be observed from the above description that my invention provides a relatively light spool of simplified construction which is economical to manufacture and strong and durable in use. The improved form of coupling-element or gudgeon for the end-journals of the spool provides for connecting the spool units at their abutting ends with a positive clutching action while eliminating the use of axial spindles, pintles, or other machined parts requiring screw-threads for holding them in place. The gudgeons are securely attached directly to the end-heads of the spool by means of the lugs formed integral therewith and their cooperating clutch-faces are designed to provide for economical methods of manufacture with a minimum of machining operations.

The improved form of the spool barrel,

comprising integral holding- or seizing- means for the ends of the yarns wound thereon, also makes for greater simplicity in the structure of the spool while still further economizing in the cost of manufacture.

Various other modifications besides those herein shown may be made in the form and structure of the parts of the improved spool without departing from the spirit or scope 10 of the invention; therefore, without limiting myself to the exact embodiment disclosed, I claim:

1. A tuft-yarn spool for the carrier-frames of looms comprising a cylindrical barrel having end-heads, and hollow cylindrical gudgeons arranged coaxially of the heads and projecting outwardly therefrom with integral clutch-elements at their ends adapted for interlocking engagement one 20 with another when the spools are placed end-for-end in series.

2. A tuft-yarn spool for the purpose specified comprising a cylindrical barrel, sheet-metal heads secured to the ends of the barrel, and tubular sheet-metal gudgeons projecting axially from the heads and formed with clutch faces at their ends adapted for interlocking engagement one with another when the spools are placed end-for-end in 30 series.

3. A tuft-yarn spool for the purpose specified constructed with a tubular barrel having integral projecting lugs at its ends, sheet-metal end-heads having openings receiving 35 the lugs on the barrel which are riveted therethrough, and tubular sheet-metal gudgeons having integral end lugs which are also riveted through openings in the end-heads, the outer ends of the gudgeons being 40 formed with integral clutch-elements adapted for interlocking engagement one with another when the spools are arranged in series in axial alinement.

4. A tuft-yarn spool for the purpose specified comprising a barrel with sheet-metal heads at the ends thereof, and tubular gudgeons provided with end-lugs riveted through openings in the heads to fasten them 45 in position coaxially thereof, the opposite 50 ends of the gudgeons being cut away in

castellated form to provide cooperating clutching-faces adapted for interlocking engagement when a plurality of spools are placed end-for-end in axial alinement with the gudgeons seated in their bearings.

5. A tuft-yarn spool for the purpose specified comprising a cylindrical barrel, heads at the ends of the barrel, and gudgeons projecting axially from the heads, said barrel formed of sheet-metal with a seam extending longitudinally thereof, the edges of the seam being crimped over to project radially outward whereby to form an exterior rib adapted to grip the ends of the 60 yarns wound onto the barrel.

6. A tuft-yarn spool for the purpose specified comprising a cylindrical barrel, heads at the ends of the barrel, and gudgeons projecting axially from the heads, said barrel constructed from a sheet-metal strip 70 rolled into cylindrical form with its edges meeting in a seam and crimped to project radially outward to provide a longitudinally-extending exterior rib, the projecting portion of the rib being knurled or roughened on its surface to adapt it to grip the 75 ends of the yarns wound onto the barrel.

7. A yarn spool for a tube frame comprising a yarn-carrying barrel and end heads, each head being provided with a concentrically arranged number of spaced 80 prongs projecting axially from the spool and adapted to form a journal for rotatably supporting the spool and capable of interlocking with a similar journal of an adjacent 85 spool to transmit rotation, substantially as described.

8. A yarn spool for tube frames embracing a longitudinal barrel for carrying the yarn transverse heads, a plurality of spaced 90 prongs located around the central axis of the spool and projecting endwise beyond the heads to form intermatching engagement with similar prongs on an adjacent 95 spool to produce equal rotation of two adjacent spools, substantially as described.

In testimony whereof I affix my signature.

FRANK MOSSBERG.
